UNITED STATES PATENT OFFICE.

JOKSHAN F. WITTMANN, OF ST. LOUIS, MISSOURI.

AIR-COOLER FOR ENGINES.

1,336,457.

Specification of Letters Patent. Patented Apr. 13, 1920.

Application filed June 2, 1919. Serial No. 301,213.

To all whom it may concern:

Be it known that I, JOKSHAN F. WITTMANN, a citizen of the United States, residing at St. Louis, State of Missouri, have invented certain new and useful Improvements in Air-Coolers for Engines, of which the following is a full, clear, and exact description, reference being had to the accompanying drawings, forming a part hereof.

10 The present invention is directed to improvements in air coolers for internal combustion engines, particularly those employed in connection with automobiles or self-propelled vehicles, the object of the invention being to substitute suitable air cooling means for the conventional radiators and water circulating systems so generally employed. The use of an air cooling system materially simplifies the structure, eliminates troublesome leaks, and at the same time reduces the weight by dispensing with the radiator. It possesses further and other advantages better apparent from the following detailed description of the invention in connection with the accompanying drawings in which—

Figure 1 represents a side elevation of an automobile with part of the hood removed showing my invention applied to the engine of the car; Fig. 2 is an enlarged side elevation of the engine and invention applied thereto with parts broken away; Fig. 3 is a top plan of the air moving apparatus for circulating the air; Fig. 4 is an enlarged front elevation of the air moving apparatus; Fig. 5 is an enlarged side elevation of the same; and Fig. 6 is a middle vertical transverse section on the line 6—6 of Fig. 4.

Referring to the drawings, A, represents an automobile provided with an engine E, the cylinders 1 whereof are surrounded by an air jacket s, for the circulation of the cooling medium or air employed under the present system. Tapping the inner side wall 45 of the jacket at the middle and, near the bottom thereof is one end of a circulating pipe or conduit 2, the opposite end of the pipe connecting to the fan or blower casing 3 mounted at the front of the car, said 50 casing being provided with a fan or blower 4 mounted on a shaft 5. Tapping the top of the jacket s at the front end is one end of a circulating pipe or conduit 6, the opposite end of the pipe connecting to the fan 55 casing 7 provided with an exhaust fan 8 mounted on the shaft 5. The fan casings

3 and 7 are preferably made in sections or halves a, a, and a', a', respectively, the respective sections and casings being secured together by bolts b, b, as shown, and supported in front of the engine by the brackets 9, 9, mounted on the frame F of the chassis, the tops of the brackets being engaged by the angle pieces 10, 10, bolted to the fan casings. Any other method of securing the 60 fan casings to the car could obviously be resorted to. The opposite faces of the fan casings are provided with bearings 11 for the partial support of the fan-shaft 5, said bearings being equipped with oil cups 12 for 65 lubricating the shaft, the latter being provided with a belt-pulley 13 on the end adjacent the engine, said end being supported by a bracket d leading from the gear-case C. The fans 4 and 8 are secured to the 70 shaft 5 by set screws 14 as shown (Fig. 6). The casing 3 is provided with a bottom intake leg 15, and a top discharge leg 16 to which the pipe 2 is directly coupled; and the casing 7 is provided with a top intake 75 leg 17 to which the pipe 6 is coupled, and with a bottom discharge leg 18. The leg 15 is provided with an intake elbow 19 into which the outside air is directly drawn, the engine and fans being inclosed in a hood H 80 preferably provided at the front with a screen H' for filtering the air and excluding dust, dirt, and solid particles from the fan casings. In the present embodiment of the invention I provide the usual cam-shaft 20 85 of the engine with a belt-pulley 21 which is connected to the pulley 13 on the shaft 5 by a belt 22.

When the engine is running the pulley 13 is rapidly driven by the cam shaft, the fans 95 4 and 8 being rapidly revolved in their respective casings. Atmospheric air is thereby sucked into the casing 3 through the elbow 19 (which is placed in front of the engine so as to get as large a complement of cool 100 air as possible), and blown out of the leg 16 through the pipe 2 and into the air jacket or space s around the engine cylinders. The air jacket s, it is seen, thus takes the place of the well known water jacket, when 105 water is used as a cooling medium. The cool air is forced through the air jacket around the engine cylinders by the blower 4, taking up the heat of the cylinders and is finally sucked out through the pipe 6 by 110 the exhaust fan 8 into and through the casing 7, and finally is expelled through the leg

18. A constant and rapid circulation of air keeps the cylinders cool and is not subject to leaks as is the case where water is circulated through a radiator; and, of course, 5 does not freeze in cold weather. It is obvious of course that one of the fans might be dispensed with so far as the invention is concerned, but in practice the arrangement here shown constitutes the most practical ar- 10 rangement for accomplishing the results desired, and for bringing about an effective and positive circulation of the cooling medium or air. The apparatus might be altered in many particulars without involv- 15 ing a departure from the nature or spirit of the invention. For example, as shown, only a single air-jacket surrounds the several cylinders of the engine; but obviously we may have a separate jacket for each cylinder 20 with suitable means for either establishing inter communication between the jackets, or a separate communication with the circulat- 25 ing conduits 2 and 6 or their equivalent. To maintain an effective and frictionless circulation, the intake end of the conduit 2 should be substantially diametrically oppo- 30 site the intake elbow 19, and the discharge end thereof should tap the air-jacket at or near the bottom; the discharge end of the 35 conduit 6 should be substantially diametri- cally opposite the exhaust leg 18, and the intake end thereof should tap the air-jacket at or near the top, the casings 3 and 7 being juxtaposed and the legs 15, 17, and 16, 18, being respectively diagonally opposite one another.

Having described my invention what I claim is:

1. In combination with an internal com- 40 bustion engine provided with cylinders, an air jacket surrounding said cylinders, a fan blower mounted in front of the engine, means for supporting said engine and blower, a circulating pipe leading from the 45 blower to the bottom of the air jacket, an exhaust fan mounted in front of the engine, an exhaust pipe leading from the top of the

air jacket to the exhaust fan, and driving means for said fans.

2. In combination with an internal com- 50 bustion engine provided with cylinders, a frame supporting said engine, an air jacket surrounding said cylinders, a fan blower mounted in front of the engine, a bracket on the aforesaid frame for supporting said 55 blower, a circulating pipe leading from the blower to the air jacket, an exhaust fan mounted in front of the engine and supported by the aforesaid bracket, an exhaust pipe leading from the air jacket to the ex- 60 haust fan, driving means for said fans, a hood inclosing the engine and fans, and a screen in front of the hood.

3. In an air cooling system for internal combustion cylinder types of engines for 65 self-propelled vehicles, an engine, an air-jacket surrounding the cylinders thereof, a blower and casing therefor, a circulating conduit connecting the blower casing with the bottom of the air jacket, an exhaust fan 70 and casing therefor, a circulating exhaust conduit leading from the top of the air jacket to the casing of the exhaust fan, an intake for the blower casing substantially diametrically opposite to the intake of the 75 circulating conduit leading therefrom, an exhaust leg for the casing of the exhaust fan disposed substantially diametrically op- 80 posite the discharge end of the circulating conduit leading therefrom, the casings of the blower and exhauster being juxtaposed, the intake leg of the former being diag- 85 onally opposite the intake leg of the latter, and the outlet leg of the blower being diag- onally opposite the outlet of the exhauster, and means for driving the blower and ex- haust fan from the engine aforesaid.

In testimony whereof I affix my signature in presence of two witnesses.

JOKSHAN F. WITTMANN.
